Primary Examiner—Raphael Barkai
Attorney, Agent, or Firm—Wolf, Greenfield & Sacks, P.C.[57] **CLAIM**

The ornamental design for a toy tow truck, as shown and described.

DESCRIPTION

FIG. 1 is a right side elevation view of a toy tow truck showing my new design, the side opposite is a mirror image;

FIG. 2 is a top plan view thereof;

FIG. 3 is a front view thereof; and,

FIG. 4 is a rear view thereof.

The cross hatching is a feature of the design.
